UNITED STATES PATENT OFFICE.

WALTER PHILLIP POTTER AND CHARLES F. HANDSHY, OF SPRINGFIELD, ILLINOIS.

TICKET BOX AND CUTTER.

1,315,404.

Specification of Letters Patent.

Patented Sept. 9, 1919.

Application filed August 18, 1917. Serial No. 186,999.

To all whom it may concern:

Be it known that we, WALTER P. POTTER and CHARLES F. HANDSHY, citizens of the United States, residing at Springfield, in the 5 county of Sangamon and State of Illinois, have invented certain new and useful Improvements in Ticket Boxes and Cutters, of which the following is a specification.

Our present invention relates to improvements 10 in ticket boxes and cutters, designed especially for use in connection with railway tickets or transfers for indicating the destination on the ticket for which it is sold, or the transfer point for which the transfer 15 is issued. The device is especially adapted for use in connection with specially designed and arranged tickets, by means of which the destination may be indicated on the passenger's ticket and simultaneously indicated 20 on a duplicate column, the destination of the ticket on the agent's stub. And in connection with the box and cutter, a round trip or return ticket is used and the destination for both trips of the round trip 25 ticket may be notched simultaneously together with a similar identification of the destination on the agent's stub.

The invention consists essentially in the adaptation for use with the above indicated 30 tickets, of a box for holding the tickets in a pack, and specially designed means for cutting the ticket which is both adjustable and removable with relation to the box, and which may be manipulated with precision 35 and facility in issuing tickets or transfers.

In the accompanying drawings we have illustrated one complete example of the physical embodiment of our invention constructed according to the best mode we have 40 so far devised for the practical application of the principles of our invention.

Figure 1 is a perspective view of the box and cutter with a stack or pack of railway tickets indicated therein.

Fig. 2 is a transverse sectional view of the device of Fig. 1.

Fig. 3 is a blank outline showing the agent's stub and destination for which the ticket was issued.

Fig. 3^a is a blank form indicating the ticket with its destination notched thereon.

Fig. 4 is a perspective view of the empty box.

Fig. 5 is perspective view of the pressure plate and cutter.

Fig. 6 is a view of the supporting bar for 60 slidble cutter.

Fig. 7 is an enlarged sectional view of the pressure plate and supporting bar showing the cutter in elevation.

In the preferred embodiment of our invention we utilize a single trip ticket with two columns for the railway stations, of which the column to the right is printed in large black type and the left column is 65 printed with a duplicate list of stations paralleling the ticket stations, but preferably in smaller or lighter type, and this ticket is adapted to be torn apart longitudinally to provide the passenger's ticket and the stub 70 to be retained by the agent. When the ticket is torn apart, a notch is provided pointed to the destination on the ticket, and a complementary dart is fashioned on the agent's stub opposite the destination, and in 75 this manner the ticket issued and the stub retained are precisely and quickly marked.

The device is to be manipulated by hand and to this end, the metallic box 1 is of convenient size to be grasped in the left hand 80 and neatly fits the stack or pack of tickets therein, the side walls 2, 2 being cut away at both the back and front to give free access to the tickets. Slots 3, 3, are provided in the opposite ends 4, 4 of the box, and along 85 the outside ends are attached two spring arms 5, 5 having their ends projecting beyond the slots 3 for a purpose to be described.

In connection with the box a removable 90 pressure plate 6 is employed, and designed to bear down upon the stack of tickets. At its front the plate is formed with a beveled edge or knife edge 7 along which the ticket may be torn, and at its ends integral perforated ears 8, 8' rise therefrom to support the guide bar 9 which extends parallel with the plate and is spaced a slight distance therefrom. The plate is adapted to lie in the box on top of the tickets and the bar is so 95 positioned that its ends will project through the slots 3 so that the slots 10, 10 in the ends of the bar may be engaged by the spring arms 5 by which the plate and bar are retained in position in the box. The grooved 100 bar and spring arms prevent longitudinal movement of the bar, but retain the plate and bar in position so that they may follow the diminishing pack of tickets as they are taken from the box.

A slidable cutter blade 11 with a forward cutting edge 12 has a perforated boss 13 through which the bar 9 passes, the perforation being indicated at 11^a, and it will 5 readily be apparent that the cutter blade may be slid lengthwise on the supporting bar as desired.

In operation, the box as shown in Fig. 1 is grasped in the left hand, and if the destination desired is "Hawks", the cutter blade 10 is moved to position so that the cutting edge will point to the word Hawks. Then the edge of the ticket is lifted by a finger 15 of the right hand and the ticket held in the hand and torn along the beveled edge of the pressure plate until the cutting edge of the blade is reached. The thumb is bearing down on the blade, and as the supporting bar is somewhat resilient, the cutting portion 20 of the blade is pressed firmly upon the ticket so that the ticket may be torn around the cutting edge or point leaving the notch shown in Fig. 3^a, and then the ticket is torn to its lower end, thus freeing the ticket 25 for the passenger and the stub is retained by the agent. For convenience of illustration, most of the stations have been omitted from the showing on the ticket, but it will be apparent that the cutting blade or cutter 30 may be slid along to any destination desired, and the ticket torn off as above described, with facility and precision.

When the tickets have been exhausted, the 35 spring arms are freed from the grooved bars and the plate and bar with the cutter may be removed bodily from the box, a new pack of tickets inserted in the box, and then the cutting device again located in the box and held by the spring arms.

Copies of this patent may be obtained for five cents each, by addressing the "Commissioner of Patents, Washington, D. C."

What we claim is:—

1. A ticket holder and cutter comprising 40 a container adapted to receive superposed tickets, said container having suitable walls, a vertically adjustable pressure member having a cutter thereon resting on the tickets 45 and extending across the container, a resilient member connected with the container and near one end slidably engaging the pressure bar with its end portion normally free from said bar whereby the resilient element may 50 be shifted from engagement with the pressure bar when in position in said container to permit the same to be bodily removed from the container.

2. In a device of the character described, 55 a ticket container, a pressure member adapted to overlie tickets in the container, said container having means guiding the pressure member during its vertical movement, and means for maintaining the pressure member in operative association with the container and its guiding means including resilient elements having free end portions slidably engaging the pressure member to exert a pressure on the ladder, the 60 free ends of said resilient elements extending beyond the pressure member when in operative position and entirely disconnected therefrom, whereby the resilient elements 65 may be shifted from contact with the pressure member when the same is in operative position to permit the same to be bodily removed from the container.

In testimony whereof we affix our signatures.

WALTER PHILLIP POTTER.
CHARLES F. HANDSHY.
